AUTOMATIC SPACE DRIER

James W. Case, Fairfax, Va.

Application September 8, 1947, Serial No. 772,830

9 Claims. (Cl. 183—4.1)

(Granted under the act of March 3, 1883, as amended April 30, 1928; 370 O. G. 757)

1

My invention relates to improvements in dehumidifiers and more particularly relates an automatic space dryer for automatically controlling the degree of moisture in a cabinet below a safe maximum level.

The purpose of the invention is to provide an inexpensive and compact dehumidifier unit which is self-reactivating and particularly suitable for the protection of delicate instruments and machinery against corrosion and general damage due to moisture.

It has been well recognized that the main source of deterioration and maintenance troubles in many types of ordnance gear, particularly those which are composed of intricate electrical, mechanical or optical components in sealed or unsealed housings, is moisture. The presence of moisture in such units, either as absorbed moisture in metallic and nonmetallic surfaces, condensed moisture on such surfaces, or in the atmosphere surrounding the components, may lead to metallic corrosion, loss of electrical resistance, fogging of optical objectives, or mold growth on insulation, thus making the equipment unusable in service or reducing it to the last stages of deterioration during shipment, storage or periods of disuse.

As a result of research undertaken by the Armed Forces during the past few years in developing means for preservation of ordnance equipment on a long term basis, it has been generally found that dehumidification of the atmosphere in which equipment is stored is by far the most practicable means of protecting large amounts of material, particularly that which must be preserved in a fully assembled condition, due to military readiness requirements. It has been proven by comparative tests that a controlled relative humidity of 30% or below will effectively prevent corrosion and mold growth on all components of ship machinery and ordnance equipment which are susceptible to them. It has also been found that a relative humidity of 50% or below will measurably extend the life of equipment and is recommended if 30% cannot be economically obtained; further, that materials such as silk and other fabrics require storage within a definite humidity range to insure maximum strength of their fibers.

The moisture hazard to ordnance equipment would be entirely eliminated if operating units were thoroughly dried out during initial assembly and enclosed in durable hermetically sealed, moistureproof cabinets. While this has been partially accomplished in the design of optical equipment,

these units must be dried out with special drying equipment or re-gassed with nitrogen or helium at intervals because they are susceptible to leakage through stuffing glands and objective mountings. The majority of all other types of fire control units are enclosed in so-called "water-tight housings." While these housings, or more broadly cabinets, are usually made of cast aluminum, bronze, sheet steel, etc., the multiplicity of drive shafting, control shafting, electrical conduit connections and access door gaskets which they incorporate, makes them susceptible to breathing and internal moisture condensation, due to temperature changes which are caused by atmospheric fluctuations or variations in dissipated heat from the units.

My present invention contemplates automatically maintaining the interiors of such cabinets at a safe maximum value of relative humidity by use of a self-reactivating desiccant to adsorb all moisture which gains ingress due to breathing or diffusion through housing walls or sealed joints. Previous systems for accomplishing this result have been cumbersome, bulky and insusceptible of precise and delicate adjustment without servicing over long periods of time. Therefore, due to the extremely limited applications of such systems, no general use has been made of dehumidifying apparatus for instrument housings or equivalent cabinets.

The primary object of my invention, therefore, is to provide dehumidifying apparatus for cabinets, including moisture adsorbing means, which is automatically reactivated during operation of the apparatus.

Another object of the invention is to provide dehumidifying apparatus including automatic reactivating means, wherein the reactivation is controlled by the weight of the moisture adsorbing means itself.

Still another object of the invention is to provide dehumidifying apparatus including automatic reactivating means, wherein the combined dehumidification and reactivation cycle maintains the atmosphere below a pre-set maximum value of relative humidity.

Still a further object of my invention is the provision of a compact, portable and inexpensive automatic dehumidification unit.

Other objects and advantages will become apparent from the following description of a preferred embodiment of the invention which has been described in detail in connection with the accompanying drawing in which:

Figure 1 is a side elevational view, partially in

section, showing the dehumidification apparatus incorporating the present invention.

Figure 2 is a schematic view of the electrical circuit control means for the automatic space dryer of my invention.

Referring to Figure 1, it will be seen that the complete automatic space dryer unit is placed within an appropriate moisture barrier such, for example, as the cabinet 1, to be dehumidified. It may, in fact, be incorporated as a component of the complete instrument. Inlet port 12, intake conduit 14 and port 15 permit intake of reactivating air from outside the cabinet 1 into the casing 3 of the space dryer unit. A conventional blower 8 operated by motor 9 causes reactivating air to be drawn through casing 3 and exhausted to the outer atmosphere through a conduit and outlet port (not shown) which are duplicates of 14 and 15 respectively. The housing 5, preferably of perforated sheet metal, contains the moisture adsorbent material 4, such as silica gel, attracts particles of moisture vapor from the free space enclosed by the cabinet 1, into the interior of the casing 3 and thence to the moisture adsorbent material 4 through a plurality of moisture porous membranes 2 lodged within the casing 3. In a specific embodiment of my invention, these moisture porous membranes consist of four equally spaced windows of glass cloth or unbleached muslin. Other materials and arrangements thereof may be utilized to obtain the maximum possible area for economical moisture diffusion rate. A spring 6 adjustable by nut 16 acts as a bias against the weight of the moisture adsorbent material 4. The switch actuator bar 17, held within limit stops 18 and 18' operates a low weight differential switch 7, of any well-known design, by depressing pin 19.

Referring to Figure 2, it will be seen that closing of the contacts 11 of the switch 7 places the motor 9 and heating element 10 across the electrical power line.

Referring again to Figure 1, it will be seen that in the static condition, the moisture of the air within the chamber 1 to be dehumidified permeates through the moisture-porous windows 2 lodged within the casing 3 of the space dryer unit. The purpose of these moisture-porous membranes is to permit the air contained in the instrument housing 1 which is to be dehumidified, to enter the space dryer unit during the static condition of operation, while acting during the reactivation cycle, as a baffle against the purging of reactivating air which may be as high as 100% relative humidity and inhibiting it from entering the free air space of the casing 1.

In the static condition, the weight of the moisture adsorbent material 4, contained within the perforated housing 5, is very delicately balanced against the bias of spring 6, adjustable by nut 16, and is insufficient to actuate the switch 7. When, however, the dehumidifying unit is ready for reactivation, i. e., when the moisture adsorbent material has taken up sufficient water to overcome the bias of the spring 6, the weight of the moisture adsorbent material 4 causes the switch actuator or bar 17 to operate the switch 7 by depressing pin 19. This initiates the reactivation cycle.

As seen in Figure 2, the contacts 11 of the switch 7 when closed, make the electrical circuit to the motor 9 and heating elements 10. As seen Figure 1, heating elements 10, embedded within the moisture adsorbent material 4, serve to evaporate moisture from the moisture ad-

5 sorbent material during the reactivation process. Blower 8, when operated by motor 9, causes purging air to be drawn into the unit through inlet port 12, conduit 14, and port 15 which communicates with the dehumidifier unit. The immediate effect of the flow of air is a pressure drop in the port 15 and in the interior of the casing 3. The purging air circulates through the casing 3 taking up moisture vapor which is being liberated from the porous housing 5 and is then drawn through the blower 8 and is forced from the blower outlet into a conduit (similar to conduit 14) which leads to the reactivation air outlet (not shown) to exhaust into the outer atmosphere, leaving the moisture adsorbent material purged of moisture and then ready for another cycle of static drying operation. The reason why the purging air and its moisture content do not migrate reversely through the membranes 2 is that the slight pressure drop inside of the casing 3 prevents it. The pressure in the cabinet would be substantially that of the external atmosphere so that if any migration takes place during purging it would be from the cabinet 1, through the membranes 2 into the casing 3. It will now be clear that the next cycle is initiated by the opening of the contacts 11 of switch 7, since the weight of the reactivated moisture-adsorbent material is now insufficient to overcome the bias of the spring 6. The operation of the motor 9 for the blower 8 and the heating of element 10 is now stopped and the dehumidifier unit is ready for another stage of dehumidification.

35 The length of the conduit 14, and its equal (not shown) at the blower exhaust should be very large in relation to their internal diameter. A ratio of length to diameter of 40 to 1 is preferable, in order that moisture vapor is inhibited from entering the space of the cabinet 1, from the outer atmosphere, during the static drying phase and that, during the reactivation phase, free entry and passage of purging air through the space dryer unit may be permitted.

40 An added and useful purpose is provided by the conduit 14 and its equal at the blower exhaust, wherein they permit free breathing of the cabinet, during diurnal temperature change, thereby permitting great simplification in the design of such cabinet, packing, access door seals, etc. In addition, such breathing action forces the exchanged air to pass either through or adjacent to the body of moisture adsorbent material 4, which thereby takes up excess moisture from the air entering the cabinet 1 and later discharges it by the reactivation process previously described.

45 In contemplation of the use of this invention for those applications requiring control of the relative humidity within a specified range, a spring adjustment 16 shown on the control switch 7 in Figure 1 may be utilized to set in advance the desired humidity level. This feature is based upon the known characteristic of silica-gel to adsorb an amount of moisture dependent upon the relative humidity of the air surrounding it. For example, suppose that the adjusting nut is present to close the switch contacts at 5.2 pounds total weight, or 4 pounds dry weight plus 1.2 pounds of moisture. The latter corresponds to the saturation value or an equilibrium condition of silica-gel at 50% RH. Now suppose that dehumidification of the space in the cabinet starts with the RH level at 70%. When moisture adsorption by the desiccant

reaches 1.2 pounds, reactivation will automatically take place and reduce the adsorbed weight $\frac{1}{2}$ oz. (the switch operating differential), thereby permitting the desiccant to take up more moisture and further reduce the RH of the space. It may take one or more steps of operation for the unit to bring the RH of the space down to 50% and when this is reached the unit will continue to operate the desiccant at saturation corresponding to 50% RH with occasional reactivations, depending upon the rate of ingress of moisture to the housing. Other levels of relative humidity may be obtained by presetting the pointer 20, to a desired value shown on the graduated scale 21.

It is clear that various modifications in construction and arrangement of parts may be made without departure from the spirit and scope of the present invention and the invention is not therefore limited by the illustration of the specific preferred example or otherwise than by the appended set of claims.

The invention herein described may be manufactured and used by or for the Government of the United States of America for governmental purposes without the payment of any royalties thereon or therefor.

I claim:

1. A dehumidifying apparatus comprising in combination, an outer casing having a plurality of moisture-permeable membranes, an inner perforated housing, means movably supporting said housing, a body of moisture adsorbent material contained within said inner perforated housing, a blower having associated air conduits communicating with said outer casing for passing a stream of air between said casing and housing for purging said moisture adsorbent material, heating elements associated with said body for drying said body, and an adjustable automatic electric control mechanism, substantially instantaneous in operation, said mechanism being operable by said supporting means when moved in response to variations in the weight of the moisture content of the adsorbent material at various relative humidities for controlling the operation of said blower and heating elements.

2. The combination defined in claim 1 above wherein said conduits are characterized further, in that their length is at least forty diameters, whereby to inhibit moisture intrusion into said casing.

3. Dehumidifying apparatus comprising a unit installable in a substantially closed cabinet, a desiccant for abstracting the moisture from the air in the cabinet, means for periodically flooding the desiccant in a purging air current from a source external to the cabinet and at a pressure lower than that of the cabinet, and an enclosure for the desiccant located in the cabinet, partly guiding the air current and having at least one membrane allowing slow migration of moisture in one direction to the desiccant at cabinet air pressure but acting as a barrier to reverse migration from the desiccant enclosure to the cabinet.

4. Dehumidifying apparatus comprising a cabinet subject to a humid air content at atmospheric pressure, conduits and means for producing in one of its components a current of external purging atmospheric air at reduced pressure, a desiccant in the cabinet, and means enclosing the desiccant, being in communication with the conduits and having at least one membrane penetrable by the cabinet moisture at its atmospheric

pressure but resisting reverse penetration by moisture because of the reduced pressure in said one conduit component during purging.

5. Dehumidifying apparatus comprising a casing adapted to be installed in a cabinet, intake and exhaust conduits communicating with the interior of the casing and leading to remote points of atmospheric air entrance and discharge, the discharge conduit containing a motor-operable blower for inducing a current of atmospheric air through the casing to purge it, at least one moisture-permeable membrane constituting part of the casing, being penetrable by static water vapor ambient in the cabinet but becoming a barrier to the reverse migration of water vapor during purging, a desiccant in the casing and having an embedded heating coil, said desiccant adsorbing the penetrant water vapor but yielding its excess to the purging current, an anchored spring suspending the desiccant, said spring expanding and contracting with the accretion and loss of water by the desiccant, and an electrical circuit containing the blower motor and the heating coil, and having a switch subject to closing and opening as the spring expands and contracts.

6. Dehumidifying apparatus comprising inlet and outlet conduits arranged to establish proximate and remote ends, said conduits being of a high length-to-diameter ratio to inhibit the entry of external atmospheric air at the remote ends during the static condition of the apparatus, a casing with which the proximate ends of the conduits are connected to provide intake and outlet ports, said casing being installable in a cabinet the atmosphere of which is to be controlled as to moisture content, a blower connected to the outlet port and having a motor for driving it to set up a purging air current and a pressure drop in the ports and casing due to the length of the inlet conduit, a desiccant located in the casing and having an embedded heating coil in electrical connection with the blower motor, suspension means for the desiccant yielding to an increase of desiccant weight upon its accretion of moisture during said static condition and contracting by reduction of said weight upon the loss of moisture by action of said purging air current, switch means set in operation by yielding of said suspension means to activate the motor and heating coil, and at least one membrane set in the casing, yielding to a slow migration of moisture from the cabinet to the desiccant during pressure equalization in the cabinet and casing when the apparatus is static but becoming a barrier to return migration of moisture during purging because of the pressure differential in the cabinet and casing.

7. Dehumidifying apparatus comprising the combination of a cabinet the atmosphere of which is adapted to be limited as to moisture content, a desiccant to adsorb moisture from said atmosphere, said desiccant having a heating coil embedded therein, a casing in which the desiccant is situated, said casing sheathing the desiccant from the cabinet atmosphere excepting for at least one membrane window through which the moisture is permeable toward the desiccant, supporting means by which the desiccant is sustained in the casing, said supporting means including a spring inherently yieldable to predeterminedly low gain and loss of moisture by the desiccant, and having means for its adjustment so that the yielding of the spring can be adjusted to any setting in an adopted range of probable moisture gain by the desiccant, intake and ex-

7
haust conduits communicating with the interior of the casing and leading to remote points of atmospheric air entrance and discharge, a motor-operable blower in the exhaust conduit, and a switch embodied in said supporting means, being connected with a source of electrical current and with the heating coil and blower motor, said switch being operable by movement of the desiccant upon gain or loss of moisture in low increments at any setting of the spring.

8. A dehumidifying apparatus adapted to be contained within a cabinet, said apparatus including an outer casing having a plurality of moisture-pervious membranes, a perforated housing within said casing, a body of moisture-adsorbent material contained within said perforated housing, and conduits connecting with said casing for circulating atmospheric air through said casing, to permit breathing of atmospheric air into and out of said cabinet through said membranes.

9. The combination defined in claim 8, wherein the conduit openings to said outer casing are

spaced from each other within the outer casing, and the container of adsorbent material is interposed in the path between said openings.

JAMES W. CASE.
